UNITED STATES PATENT OFFICE

160,179

SPLIT CORE VOLTMETER-AMMETER

Samuel J. Koch, Elmont, N. Y.

Application January 28, 1950, Serial No. 7,544

Term of patent 14 years

(Cl. D26—1)

To all whom it may concern:

Be it known that I, Samuel J. Koch, a citizen of the United States, resident of Elmont, in the county of Nassau, State of New York, have invented a new, original, and ornamental Design for a Split Core Voltmeter-Ammeter, of which the following is a specification, reference being had to the accompanying drawing, forming part hereof.

In the drawing,

Figure 1 is a front view of a split core voltmeter-ammeter, showing my new design,

Figure 2 is a side view thereof, and

Figure 3 is a rear view thereof.

I claim:

The ornamental design for a split core voltmeter-ammeter, substantially as shown.

SAMUEL J. KOCH.
